UNITED STATES PATENT OFFICE.

EDWARD S. LAW AND ARTHUR JACOBSON, OF CORAOPOLIS, PENNSYLVANIA

Safety Locking Device for Auto Hoods.

Application filed March 4, 1927. Serial No. 173,760.

This invention relates to attachments for motor hoods and its general object is to provide a lock device for hoods that will prevent unauthorized persons from lifting the hood and tampering with the motor or any part hereof.

A further object of the invention is to provide a key actuated lock and fastening means for motor hoods, that will positively prevent the raising of the hood by unauthorized persons and which is capable of being easily and quickly disposed to open position when unlocked.

Another object of the invention is to provide a lock and fastening device for motor hoods for vehicles and the like that is extremely simple in construction, strong and sturdy, reasonably inexpensive in manufacture and will securely hold a hood in operative position with the result that it will prevent rattling thereof.

To the attainment of the above broadly stated objects and others which will present themselves as the nature of the invention is better understood, the improvement also consists in certain other novel features of construction, combination and operative association of parts, a satisfactory embodiment of which is disclosed by the accompanying drawings.

In the drawings:

Figure 1 is a fragmentary view of a motor vehicle and showing our novel hood lock and fastening means in applied and locked position.

Figure 2 is a perspective view of the device per se.

Figure 3 is a sectional view taken on the line 3—3 of Figure 1.

Figure 4 is a sectional view taken on the line 4—4 of Figure 1.

Referring to the drawings in detail, the letter A indicates a vehicle hood, B the frame of the vehicle, and C the floor board thereof.

Secured to each side member of the frame B and preferably to the lower flange thereof, as shown in Figure 4, are guide bearings, each of which include a body 1 provided with a centrally disposed preferably square opening and extending from the body are spaced arms 2 riveted or otherwise fixed to the flange above set forth.

These guide bearings are disposed in aligned pairs as suggested in Figure 1 and receive slidable rods 3 and 4, square in cross

section to correspond to the openings of the guide bearings and each of said rods have a headed pin secured to and extending from the inner end thereof and received in slots 5 formed in the lower ends of arms 6 extending at right angles and depending in parallelism from the ends of a cross rod 7. The arms 6 are each provided with an opening 8 intermediate their ends for receiving means 9 such as a bolt and nut connection, for pivotally securing the device to the frame B as suggested in Figure 1 of the drawings.

The free ends of the rods 3 and 4 are bent at right angles upon themselves to provide uprights 10 terminating in inwardly bent tapered ends 11. Secured to the inner sides of the hood in the path of the tapered ends 11 are bearing blocks 12 provided with elongated openings to receive the tapered ends 11 for securely holding the hood in closed position, as clearly shown in Figure 1 of the drawings.

In order to lock the device in operative position, we provide a lock casing 13 having any well known key actuated lock mechanism arranged therein and a bolt 14 which is provided with a keeper or notch 15 formed in a plate 16 secured to the frame, and said lock casing is secured to the shank 17 of a foot pedal 18 arranged in convenient reach of the operator of the vehicle equipped with our device and in order to accomplish this arrangement, the shank is secured to one of the arms 6 and passed through and is pivoted in a slot 19 formed in the floor board C.

The uprights 10 are provided with an opening 20 to receive one end of coil springs 21 which have their opposite ends suitably secured to the frame and are adapted to dispose the device to open position, upon releasing the lock and pressing upon the foot pedal 18.

It is thought from the foregoing description that the advantages and novel features of the invention will be readily apparent.

We desire it to be understood that we may make changes in the construction and in the combination and arrangement of the several parts, provided that such changes fall within the scope of the appended claim.

Having described the invention, we claim:

In a locking means for a motor vehicle hood, guide bearings secured to the frame of

the vehicle, rods mounted for slidable movement in said bearings, means secured to said hood and adapted to receive one of the ends of said rods for securing the hood in closed position, a cross rod transversing the frame, arms arranged in parallelism and depending from the ends of the cross rod and being pivotally secured to said frame and the rods first mentioned, a pedal including a shank 10 fixed to one of the arms and being pivotally

secured, a plate having a notch therein and being fixed to the frame and a key actuated locking mechanism secured to said shank and including a bolt cooperating with said notch to prevent movement of the said pedal in one direction.

In testimony whereof we affix our signatures.

SANFORD S. LAW.
ARTHUR JACOBSON.
